UNITED STATES PATENT OFFICE.

NATHAN S. BEEBE, OF KANSAS CITY, MISSOURI.

PISTON-COOLING DEVICE.

1,090,774.

Specification of Letters Patent. Patented Mar. 17, 1914.

Application filed July 26, 1913. Serial No. 781,299.

To all whom it may concern:

Be it known that I, NATHAN S. BEEBE, a citizen of the United States, residing at Kansas City, in the county of Jackson and 6 State of Missouri, have invented certain new and useful Improvements in Piston-Cooling Devices, of which the following is a specification.

This invention relates to piston cooling 10 devices for use particularly in connection with explosive engines, and has for its object the production of a simple means connected with the piston and crank rod of the engine cylinder whereby an efficient circulation of air may be maintained within the piston, thus acting to cool the latter and materially reduce the tendency of carbon to collect upon its working face. This in turn diminishes the load upon the engine and materially lessens the amount of lubrication required.

Specifically this cooling means comprises a fan pivoted within the piston at one side of a baffle plate which partially divides the 25 space within the piston, and a sliding connection between the fan and the crank rod so that oscillation of the latter will cause a vibration of the fan, thereby creating a current of air which will be inward on one 30 side of the baffle plate and outward on the other side thereof.

With this object in view, my invention comprises various novel and peculiar features of construction and organization, as 35 hereinafter described and particularly pointed out in the appended claims; and to afford a full and clear understanding of the same, reference will be had to the accompanying drawing, forming a part of this 40 specification, in which—

Figure 1 is a central axial section through a piston and its connecting rod, with my improved cooling device applied thereto; Figs. 2 and 3 are sections along the line 45 II—II and III—III respectively of Fig. 1, looking in the directions of the corresponding arrows.

Referring to the drawing, my piston cooling attachment is illustrated in connection 50 with a hollow sliding piston 2 having a connecting rod 4 pivotally mounted therein on a pin 6. The piston is also provided with a baffle plate 8 arranged therein so that air may enter on one side of the plate and circulate within the piston around the front 55 end of the plate adjacent the front end of

the piston, thereafter passing out of the piston on the opposite side of the plate.

For generating the current of air, a fan 10 is carried by the piston, which is provided with an angular bracket 12 secured by rivets 14 to the rear edge of the piston at one side of the plate 8, said bracket having a pin 14 for pivoting the end of an arm 16 projecting rearwardly from the fan. 60 Near its front end, adjacent the body portion of the fan, the arm 16 carries a bolt 18, which projects toward the baffle plate 8 and has journaled thereon a slide block 20. This block is designed to operate within the 65 forked end of a bracket 22 which projects through a curved slot 24 provided in the baffle plate, and is secured by rivets 26 to the connecting rod 4 on the opposite side of 70 said plate from the fan 10.

From the foregoing it will be understood that as the piston is reciprocated by the crank connecting rod 4, the latter oscillates about the pin 6, thereby carrying the bracket 22 from one end of the slot 24 to the other. 75 This bracket carries with it the block 20 connected to the fan, the block 20 being slidably mounted in the forked end of the bracket to accommodate these movements. It is thus apparent that the fan is oscillated 80 about its pivot 14 for each oscillation of the connecting rod, and as a consequence a current of air is created within the piston about the baffle plate 8, and it is also obvious that the degree of air circulation which is developed will be directly proportional to the 85 activity of the engine. This of course tends to lower the temperature of the interior of the piston, and incidentally keeps down the temperature of the working face thereof, 90 thus tending to minimize the deposit of carbon which commonly takes place upon the piston when it becomes unduly heated. This in turn reduces the amount of work 95 required of the engine and the amount of lubrication necessary.

By the above means I succeed in materially diminishing the maintenance cost of the engine, and while I have illustrated one form or embodiment which my invention is 100 adapted to take, the same is susceptible of various changes in minor particulars, and I desire to reserve the right to such changes and modifications as may fall within the spirit and scope of the appended claims.

I claim:

1. In a device of the character described,

the combination of a hollow sliding piston, the interior of said piston being partially divided by a partition, a connecting rod, fanning means carried by said piston, and 5 connections between said means and said connecting rod whereby the angular movement of the latter will operate the former to generate an air current within the piston around said partition.

10 2. In a device of the character described, the combination of a hollow sliding piston, the interior of said piston being partially divided by a partition, a connecting rod, a fan pivotally mounted within the piston, 15 and connections between said fan and rod and extending through said partition whereby the oscillation of said rod within the piston oscillates said fan to generate an air current within the piston around said partition.

20 3. In a device of the character described, the combination of a hollow sliding piston, the interior of said piston being partially divided by a partition, a connecting rod, a fan pivotally mounted within the piston, 25 and a sliding pivotal connection between said fan and rod and extending through said partition, whereby the oscillation of said rod within the piston will oscillate said fan to generate an air current within the piston around said partition.

30 4. In a cooling device for pistons, the combination of a hollow sliding piston, the interior of said piston being partially di-

vided by a baffle partition, a bracket secured to said piston, a fan pivoted upon said bracket and extending within the piston to one side of said partition, said partition being provided with a curved slot, a slide block journaled on said fan adjacent said slot, a connecting rod, and a forked bracket carried by said rod adjacent said slot and extending through the latter into sliding engagement with said block, whereby oscillation of said rod will oscillate said fan to 45 generate air currents within the piston around said partition.

5. In a cooling device for pistons, the combination of a sliding piston, a connecting rod, a fan pivoted to said piston, and 50 connections between said rod and fan whereby angular movement of the rod relatively to the piston will oscillate the fan.

6. In a cooling device for pistons, the combination of a sliding piston, a connecting rod, a baffle plate carried by said piston, a fan pivoted to said piston at one side of said plate, and connections between said rod and fan whereby angular movement of the rod relatively to the piston will oscillate the 60 fan.

In testimony whereof, I affix my signature, in the presence of two witnesses.

NATHAN S. BEEBE.
